CLAIM

The ornamental design for a seat, as shown and described.

DESCRIPTION

FIG. 1 is a front elevational view of a seat showing my design;

FIG. 2 is a right side elevational view of the seat shown in FIG. 1, the left side elevational view being a mirror image thereof;

FIG. 3 is a top plan view of the seat shown in FIG. 2; FIG. 4 is a bottom plan view of the seat shown in FIG. 3;

FIG. 5 is a rear elevational view of the seat shown in FIG. 1;

FIG. 6 is a front elevational view of the seat of FIGS. 1-5 but modified to eliminate a line of demarcation between the upper and lower sections of the back and arm rest portions thereof;

FIG. 7 is a right side elevational view of the seat shown in FIG. 6, the left side elevational view being a mirror image thereof;

FIG. 8 is a rear elevational view of the seat shown in FIG. 6, the top and bottom plan views thereof being the same as shown in FIGS. 3 and 4;

FIG. 9 is a front elevational view of the seat of FIGS. 1-5 but modified to include an upper section of the back and arm rest portions coextensive with the lower section thereof;

FIG. 10 is a right side elevational view of the seat shown in FIG. 9, the left side elevational view being a mirror image thereof; and

FIG. 11 is a top plan view of the seat shown in FIG. 10, with the bottom plan view thereof being the same as shown in FIG. 4 and the rear elevational view thereof being the same as shown in FIG. 5.
